UNITED STATES PATENT OFFICE.

JOHN E. DORRIS, OF BUFFALO, NEW YORK.

BUBBLE-PIPE.

1,381,458.

Specification of Letters Patent. Patented June 14, 1921.

Application filed June 15, 1920. Serial No. 389,250.

To all whom it may concern:

Be it known that I, JOHN E. DORRIS, a citizen of the United States, residing at Buffalo, in the county of Erie and State of New York, have invented new and useful Improvements in Bubble-Pipes, of which the following is a specification.

This invention relates to a soap bubble pipe by which a large number of bubbles can be blown from a single charge.

It is the object of this invention to produce a pipe of this character which is simple and compact in construction, which can be manufactured at a moderate cost, and which can be conveniently carried in one's pocket without danger of its leaking.

A further object of the invention is to provide efficient and reliable means for intermittently feeding the soapy-water from the main reservoir to the supplemental or exit chamber.

In the accompanying drawings; Figure 1 is a vertical longitudinal section of one form of my improvement. Figs. 2 and 3 are horizontal sections thereof on the correspondingly numbered lines in Fig. 1. Fig. 4 is a view similar to Fig. 1, showing a modified construction. Fig. 5 is a horizontal section on line 5-5, Fig. 4.

Similar characters of reference indicate corresponding parts throughout the several views.

In the embodiment of the invention shown in Figs. 1-3, the bubble pipe comprises a tubular body 10, preferably of cigar-shaped form and constructed of two half sections made of wood, clay or similar material and permanently secured together with glue, cement or other adhesive. This body is provided with a mouth piece or portion 11 at its upper contracted end and an exit or outlet passage 12 preferably of upwardly-tapering form, at its other end. Arranged in the upper portion of this body and extending the major part of its length is a main reservoir or chamber 13 for containing soapy-water, while in the lower portion thereof is a supplemental chamber 14 which is adapted to intermittently receive a small quantity of the soapy water from the main reservoir for blowing a small number of bubbles. The main reservoir and supplemental chamber are separated or divided by a diaphragm or partition 15 which is provided with a connecting passage 16. This

passage is controlled by a suitable gravity valve 17, constructed of lead or similar material, which is adapted to open upwardly toward the mouth piece 11. The stem 18 of this valve extends vertically downward through the passage 16 and is provided at its lower end with a head 19 which serves as a stop for limiting the opening movement of said valve.

Connecting the mouth piece 11 of the pipe with the supplemental chamber 14 and preferably extending through the main reservoir 13 and diaphragm 15 is an air blowing passage or tube 20 which may be constructed of thin metal tubing, glass or similar material.

To permit of filling the main reservoir with soapy water, it is provided in its upper end with an opening 21 closed by a suitable plug 22.

After filling the reservoir 13, the user shakes the pipe smartly to open the valve 17 and allow a small quantity of the soapy water to enter the supplemental chamber 14 through the passage 16 in the diaphragm. Upon blowing through the air tube 20, the film, extending over the lower end of the exit passage 12 will be formed into a bubble, and upon shaking it off by a slight jerk of the pipe to one side, and blowing again, another bubble will be formed, and so on until the supplemental chamber is exhausted, when the pipe is again shaken smartly, to allow the gravity valve to open and admit another supply to said chamber.

In the modification shown in Figs. 4 and 5, the body of the pipe is cylindrical in shape, and comprises a tube 25 of glass, wood or other material, being open at either end and having a mouth piece 26 secured in its upper end and an exit or outlet plug 27 secured in its lower end. The tube is divided by a diaphragm 28 into a main reservoir 29 and a supplemental chamber 30, the passage in the diaphragm being controlled by a valve 17^a identical with that of the preferred construction. The mouth piece is connected with the supplemental chamber by an air tube 31. The members 26, 27 and 28 may be made of wood or similar material and suitably held in the glass tube 25.

As a whole, this bubble pipe is exceedingly simple in construction, and being composed of few parts, can be manufactured

at a low cost. Furthermore, it is compact and non-leakable, rendering it capable of being carried in one's pocket.

I claim as my invention:

- 5 1. A soap bubble pipe comprising a main reservoir for soapy water, a supplemental chamber disposed in substantial alinement with said main reservoir and having an outlet passage, a diaphragm separating said reservoir from said supplemental chamber and having a passage therein connecting the latter and said reservoir, a gravity valve controlling said passage, and an air tube extending through said reservoir and communicating with said supplemental chamber.
- 10 2. A soap bubble pipe comprising a tubular body having a mouthpiece at one end and an outlet passage at its other end, a main reservoir for soapy water arranged in the upper portion of said body, a supplemental chamber arranged in the lower portion of said body and communicating with said outlet passage, a diaphragm dividing said reservoir and said supplemental chamber and having a passage therein connecting the latter and said reservoir, a gravity valve controlling said passage, and an air tube connecting said mouthpiece with said supplemental chamber.
- 15 3. A soap bubble pipe comprising a tubular body having a mouthpiece at one end and an outlet passage at its other end, a main reservoir for soapy water arranged in the upper portion of said body, a supplemental chamber arranged in the lower portion of said body and communicating with said outlet passage, a diaphragm dividing said reservoir and said supplemental chamber and having a passage therein connecting the latter and said reservoir, a gravity valve controlling said passage, and an air tube connecting said mouthpiece with said supplemental chamber.
- 20 4. A soap bubble pipe comprising a main reservoir for soapy water, a supplemental chamber arranged directly below said reservoir and having an exit passage, a diaphragm dividing the latter and said supplemental chamber and provided with a passage, a gravity valve controlling said passage and opening toward said reservoir, a stop for limiting the opening movement of said valve, an air passage extending centrally through said reservoir and communicating with said supplemental chamber, and a filling opening arranged in the upper portion of said reservoir.

lar body having a mouthpiece at one end and an outlet passage at its other end, a main reservoir for soapy water arranged in the upper portion of said body and extending the major portion of its length, a supplemental chamber arranged in the lower portion of said body and communicating with said outlet passage, a diaphragm dividing said reservoir and said supplemental chamber and having passages therein, a gravity valve controlling one of said passages, and an air tube connecting said mouthpiece with said supplemental chamber and having its lower end arranged in the other passage of said diaphragm.

4. A soap bubble pipe comprising a main reservoir for soapy water, a supplemental chamber arranged directly below said reservoir and having an exit passage, a diaphragm dividing the latter and said supplemental chamber and provided with a passage, a gravity valve controlling said passage and opening toward said reservoir, a stop for limiting the opening movement of said valve, an air passage extending centrally through said reservoir and communicating with said supplemental chamber, and a filling opening arranged in the upper portion of said reservoir.

JOHN E. DORRIS.
